UNITED STATES PATENT OFFICE.

WILLIAM R. COON, OF GOWANDA, NEW YORK.

DEVICE FOR FASTENING FOLDED PAPERS.

No. 812,115.

Specification of Letters Patent.

Patented Feb. 6, 1906.

Application filed November 28, 1904. Serial No. 234,582.

To all whom it may concern:

Be it known that I, WILLIAM R. COON, a citizen of the United States, residing at Gowanda, in the county of Cattaraugus and 5 State of New York, have invented a new and useful Improvement in Devices for Fastening Folded Papers, of which the following is a specification.

This invention is an improved means for 10 fastening folded papers.

At the present time it is customary with 15 large commercial or industrial concerns to have combination vouchers and checks, and this combination instrument is commonly 20 folded so as to expose the check and conceal the items of the voucher or other instrument; and it is the object of securing the edges of the combination folded instrument without the aid of paper-fasteners that my invention 25 has been devised; and, broadly speaking, it consists, essentially, in folding one edge of the sheet and securing said folded edge at one or more points, thereby providing a pocket into which the opposing edge can be inserted 30 and held.

The invention consists also in certain details of construction, hereinafter fully described, and pointed out in the claims.

While my invention is particularly adapt- 35 ed for combination vouchers and checks, it will of course be understood that it can be used upon all kinds of instruments which must necessarily pass through a number of different persons' hands and the contents of 40 which it is desired to protect in a measure and still leave the sheet in such a condition that it can be readily opened and inspected when desired.

In the drawings forming a part of this speci- 45 fication, Figure 1 is a perspective view of a sheet folded and secured in accordance with my invention. Fig. 2 is a detail perspective view showing one edge of the sheet about to be inserted beneath the folded opposing edge 50 of the sheet. Fig. 3 is a similar view showing a slight modification. Fig. 4 is a plan view of the blank prior to folding and securing. Fig. 5 is an end view after folding and securing. Fig. 6 is a sectional view. Fig. 7 is 55 a detail perspective view showing a sheet folded twice and secured. Fig. 8 is a detail

perspective view showing one end of a sheet folded twice, but unsecured. Fig. 9 is a plan view of the blank adapted to be folded twice.

Referring to the drawings, A indicates a 55 sheet which is scored or creased along the line A', parallel to one edge and adjacent thereto, said edge being folded over, as shown at A², and it is provided with adhesive at each end, as shown at A³, so that the ends of the 60 folded edge can be secured, thereby leaving the main portion of the folded edge unsecured and providing a pocket. The sheet A is preferably creased or folded transversely from the line A⁴, and the opposing edge of the sheet 65 is inserted beneath the folded edge of the sheet, and in order to permit this the sheet is cut away at each end, as shown at A⁵, in order to allow for the secured ends of the folded edge. In Fig. 3 the folded edge is also 70 secured centrally, as shown at A⁶, and the opposing edge of the sheet is cut away, as shown at A⁷. This makes a double secure lock, and, if desired, the device constructed as herein 75 shown and described may be employed for private correspondence, such as return postal 80 cards and the like. In Fig. 9 I have shown a blank B which is folded transversely upon the line B' adjacent one edge and folded over, as shown at B², and provided with ad- 85hesive at B³ in order to secure the said folded edge at each end. The sheet is also scored or creased on the lines B⁴ and B⁵, and at each end on the line B⁵ the sheet is cut away, as shown at B⁶, so that when the sheet is first 90 folded upon the line B⁵ it will present exactly the same appearance as the folded sheet A, and then the double-folded sheet can be inserted beneath the folded edge, as most clearly 95 shown in Figs. 7 and 8. A sheet of this kind can be used for private correspondence or can be used as a combination voucher and check, or it can be used for various other purposes, as will be readily understood by those skilled in the art to which it pertains.

Having thus fully described my invention, what I claim as new, and desire to secure by Letters Patent, is—

1. A sheet having an uncut edge folded over upon the sheet and secured at a plurality 100 of points to the said sheet, the body of the sheet being adapted to be folded and its op-

posing edge inserted under the folded edge between the secured points.

2. A sheet having one edge folded and secured at the sides and intermediate the sides, 5 the body of the sheet being adapted to be folded and also have its opposite edge inserted beneath the folded edge of the sheet, the op-

posite edge being cut away in order to accommodate the secured portions of the folded edge.

WILLIAM R. COON.
